UNITED STATES PATENT OFFICE.

GEORGE F. HAUF, OF CHICAGO, ILLINOIS, ASSIGNOR TO ROBERTSON BROTHERS MANUFACTURING COMPANY, A CORPORATION OF ILLINOIS.

EXPRESSING APPARATUS.

1,410,301.

Specification of Letters Patent. Patented Mar. 21, 1922.

Application filed November 6, 1920. Serial No. 422,202.

To all whom it may concern:

Be it known that I, GEORGE F. HAUF, a citizen of the United States, residing at Chicago, in the county of Cook and State of Illinois, have invented certain new and useful Improvements in Expressing Apparatus, of which the following is a specification.

This invention relates to expressing apparatus.

10 It is particularly adapted for use with presses employed in expressing juices from meat by-products, vegetables, fruits, grains and the like.

15 Ordinarily the products from which the extracts are taken are enclosed in cloth or fabric bags backed by wood or metal lattice-work racks and subjected to pressure.

Such expedients have been found objectionable because cloth bags quickly wear out and, 20 in many instances, can not be readily made strong enough with the required mesh. The lattice-work racks are objectionable because, in order to provide the necessary drainage, the openings must be so large that the bags often bulge into the openings and much of 25 the pressure may be wasted. Difficulty has also been experienced in obtaining the proper drainage for the expressed fluids. The filling and emptying of the bags has also been 30 a matter of considerable difficulty.

One of the objects of this invention is to provide improved apparatus for expressing processes.

Another object is to provide an improved 35 bag for use in expressing presses.

Another object is to improve the drainage from the bag.

Another object is to provide a bag which is substantially rigid and capable of with- 40 standing high pressure and severe service.

Another object is to provide a bag which may be readily filled, sealed and emptied.

Other objects and advantages of the in- 45 vention will hereinafter appear.

An embodiment of the invention and its application is illustrated in the accompany- 50 ing drawings.

The views in the drawings are as follows:

Fig. 1 is a side elevation of a bag.

55 Fig. 2 is a vertical section thereof on the line 2-2 of Fig. 1.

Fig. 3 is a horizontal section on the line 3-3 of Fig. 1.

Fig. 4 is a perspective of the bag with the 55 top or seal removed.

Fig. 5 is a top plan of a drain rack.

Fig. 6 is a side elevation thereof.

Fig. 7 is an end elevation thereof.

Fig. 8 is a diagrammatic end elevation of a press in bag filling position. 60

Fig. 9 is a diagrammatic end elevation of a press in pressing position, and

Fig. 10 is a diagrammatic end elevation of a press in bag discharging position.

The bag comprises, in general, a pair of 65 perforated side walls, a pair of hinged end walls and a hinged cover or seal.

The side walls are each made of a perforated piece of sheet metal 1 such as iron or steel. The metal used will depend to some 70 extent upon the product pressed, such metal being selected as will least affect or be affected by the products pressed and expressed.

The holes in the side walls may be 75 punched therein and their size and number will depend upon the products treated.

Each side wall is supported and strengthened by a framework to which the side wall is secured. This framework comprises a 80 top brace and support 2, side braces 3 and 4 and a bottom brace 5. The braces are secured together by suitable means, such as butt welding, and are riveted, bolted, welded or otherwise securely fastened upon the in- 85 side of their respective side walls. The two top braces 2 extend beyond the side walls to act as suspension supports for the bag, as will be hereinafter set forth.

Each end wall of the bag comprises a 90 pair of perforated metal plates or strips 6. The plates forming each end are pivotally connected together along adjacent edges by a hinge 7. The other edges of each pair of plates are pivotally connected to the inner 95 edges of the respective pair of side braces 3 and 4 by hinges 8. The hinges may be of any suitable construction.

The two hinged end walls of the bag allow 100 the bag to be opened and closed or ex- panded and contracted somewhat after the manner of an accordion. The flexibility of the walls and hinges also allow some distortion of the bag, that is the top and bottom thereof readily may be opened or closed 105 relatively different amounts. This adaptability of the bag allows the same to be readily filled and emptied as will be hereinafter described.

The cover or seal of the bag comprises 110

a pair of plates or strips 10. These plates are pivotally connected along their outer edges to the lower edges of the two top braces 2 of the bag by hinges 11. The 5 inner edge of one plate is provided with a strip of angle iron 12. The inner edge of the other plate is provided with a strip of angle iron 13. Each angle iron extends slightly beyond the opposite ends of the bag. 10 Angle iron 13 is adapted to fit over angle iron 12 when the two plates forming the cover are brought together. The two angle irons are hingedly locked together in this position by rings 14 which, when the two sections 15 of the cover or seal are brought together, are slipped over the opposite ends of angle irons 12 and 13. These rings hold angle iron 12 within angle iron 13 to effectively close and seal the top of the bag, but 20 allow the angle irons to hinge upon each other as the bag is contracted and expanded.

Extending across each side wall near the bottom thereof is a bar or strip 15. These strips serve to provide a seal at the bottom 25 of the bag when the lower ends of the side walls are brought together. The seal prevents the expulsion of the material being pressed. Each bar has a sloping upper edge to offer less resistance to the passage of the compressed material, especially when emptying 30 the bag.

The bags are reinforced and drainage therefrom is facilitated by providing a drain rack on each side thereof.

35 Figs. 5, 6 and 7 show a construction of drain rack which has been employed with success.

Each drain rack is made of a flat piece 40 of sheet metal 20. These sheets may be approximately of the same size and shape as the bags.

On opposite sides of sheet 20, corrugated sheets 21 are secured. The corrugations extend vertically of the rack.

45 Sheets 20 and 21 are secured together in any suitable manner, such for example as riveting or spot-welding the same together along the bases of the valleys of the corrugated sheets.

50 A bar 22 is secured in the top of the drain rack and extends beyond the edges thereof at each end. Bar 22 acts as a suspension support for the drain rack.

Figs. 8, 9 and 10 diagrammatically show 55 a press in three stages of an expressing process and provided with bags and drain racks as previously described.

The bags and racks may be used in other ways and on various types of presses.

60 The press illustrated is of the type commonly known as a "Berrigan" press. It has a pair of pressing platens 25, each of which is pivotally supported from the base on pivoted levers 26.

65 The platens are moved toward and away

from each other by hydraulic pressure acting through a cylinder 27, piston 28, piston rod 29 and levers 30. A suitable valve controls the operation of piston 28 by governing the flow of fluid to and from cylinder 27. The lower ends of the platens may be made to approach each other and recede by suitable screw threaded rods 31 operated through a hand wheel 32.

The opposite ends of each platen are 75 provided with brackets 35 which support a pair of suspension bars 36. The projecting ends of the top bars of the bags and drain racks hang upon bars 36.

The expressing process is carried on as 80 follows:

The desired number of bags and drain racks are hung between the platens of the press from the suspension bars. Each bag has a drain rack on each side and drain 85 racks are positioned between the outside walls of each end bag and the adjacent platen. The corrugations or grooves in the drain racks are vertically disposed to provide a large number of channels for the 90 ready flow of the expressed fluids. The drain racks engage the side walls of the bags only on the lines of contact of the apices of the ridges of the corrugations, and consequently offer little obstruction to the passage 95 of the expressed fluids through the perforated side walls of the bag. The lines of contact, however, because they are close together and extend throughout the entire depth of the bag, distribute the pressure 100 uniformly and prevent bulging.

The hinged covers of the bags are swung open so that the bags may be filled rapidly.

When the desired number of bags and racks have been hung between the platens, 105 the lower ends of the bags are closed by turning hand wheel 32 to bring the lower ends of the platens nearer together. This brings the bottom sealing bars 15 of the respective bags together effectively closing 110 the bottoms of all of the bags.

The apparatus is now in filling position shown by Fig. 8.

The bags are then filled with the material 115 to be pressed.

When the bags are all sufficiently filled the cover plates are swung together and locked by the rings 14.

The hydraulic cylinder is now operated to bring the platens of the press together. 120

During this pressing operation the hinged apices of the end and top walls of the bags move outwardly as the side walls approach each other. The expressed fluids pass through the perforations in the side and 125 end walls into any suitable receptacle. The fluid which passes through the side walls flows down the channels in the drain racks.

Fig. 9 shows a stage of the pressing operation,

Pressure is applied and maintained until the material pressed has given up its expressible fluid and then the lower ends of the bags are opened by turning hand wheel 5 32 to separate the lower ends of the platens. The discharging stage is shown in Fig. 10.

The material remaining in the bags may have been pressed to a cake which, when the lower ends of the bags are opened, will drop 10 into any suitable receptacle placed there-beneath.

Having described my invention what I claim as new and desire to secure by Letters Patent is:—

15 1. Expressing apparatus comprising a bag having hinged collapsible ends, and a corrugated rack for distributing pressure uniformly to the bag and providing drain channels for fluid expressed from material within 20 the bag.

2. Expressing apparatus comprising a metallic bag having hinged collapsible and expansible ends and top, and a channeled rack for distributing pressure uniformly to the 25 sides of the bag and acting to convey fluid expressed from material within the bag.

3. Expressing apparatus comprising a metallic bag having perforated side walls and collapsible and expansible ends, a cover 30 hinged to the side walls, and a corrugated rack providing channels for draining fluid passing out through the perforations in the side walls of the bag and distributing pressure uniformly to the side walls of the bag.

35 4. A bag for expressing processes, having a pair of perforated side walls, a pair of collapsible and expansible ends, each end comprising a pair of plates hinged together and to the respective side walls, and a top 40 comprising a pair of plates hinged on one edge to the opposite side walls and hingedly fitting together along adjacent edges.

5. A bag for expressing processes, having a pair of perforated metallic side walls, a pair of collapsible and expansible ends, each 45 end comprising a pair of plates hinged together along adjacent edges and hinged to the opposite side walls along their other edges, and a cover which may be opened for filling the bag and closed to seal the top of 50 the bag.

6. A bag for expressing processes having a pair of perforated metallic side walls, a pair of metallic collapsible and expansible ends, each end comprising a pair of plates hinged 55 together and to the side walls, a cover comprising a pair of plates each hinged along one edge to one of the side walls, and interlocking means along adjacent edges of the plates forming the cover to temporarily 60 hinge the same together and seal the top of the bag.

7. Expressing apparatus comprising a metallic bag having perforated side walls joined together by hinged sides and top, a 65 corrugated drain rack for communicating pressure to the side walls of the bag and conveying fluids expressed from material within the bag, and means for supporting the bag and rack and imparting pressure thereto. 70

8. A bag for expressing processes comprising a pair of relatively rigid side walls, and a pair of interconnecting collapsible and expansible end walls secured thereto.

9. A bag for expressing processes comprising a pair of relatively rigid side walls, one of said walls being perforated to allow 75 passage of a fluid therethrough, and a pair of interconnecting expansible and collapsible end walls hingedly secured thereto. 80

In testimony whereof I hereunto subscribe my name.

GEORGE F. HAUF.
